Primary Examiner — Austin Murphy(74) *Attorney, Agent, or Firm* — Novak Druce Connolly Bove + Quigg LLP(57) **CLAIM**

I claim the ornamental design for a card reader, as shown and described.

DESCRIPTION

FIG. 1 is a perspective view of a first embodiment of a card reader;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an alternate perspective view thereof.

The purpose of broken lines in FIG. 3 is to illustrate unclaimed portions of the article; broken lines in FIG. 8 are for illustrating environment; the broken lines form no part of the claimed design.
